[57] CLAIM

The ornamental design for an ash tray, as shown.

DESCRIPTION

FIG. 1 is a front, top and right side perspective view of an ash tray showing my new design;

FIG. 2 is a top plan view thereof;

FIG. 3 is a front elevational view thereof;

FIG. 4 is a rear elevational view thereof;

FIG. 5 is a left side elevational view thereof.

The characteristic feature of my new design resides in the radial plateau off-standing from the curved interior of the ash tray and extending from the center to the rim thereof, which plateau is provided with an elongated rectangular trim plate, as more particularly shown in FIG. 1 of the drawings.
